APPARATUS FOR DRYING OR CONDITION-
ING CIGARETTESWalter Everett Molins, Deptford, London,
EnglandApplication October 5, 1933, Serial No. 692,327
In Great Britain October 14, 1932

9 Claims. (Cl. 131—55)

The present invention consists in improved means for conditioning cigarettes or drying them, and is particularly, though not exclusively, applicable to the cigarettes as they emerge from the cigarette making machine.

The apparatus may also be used for simultaneously imparting any particular flavouring desired to the cigarettes.

The apparatus provides means for blowing a forced air draught endwise through the cigarettes, and such air may have been previously warmed or chemically dried (for instance, by calcium chloride) and it may be simultaneously blown in from one end and sucked out from the other.

In order to more evenly effect the drying of the cigarettes, the air may be blown in from one end of a cigarette for half of the available time, and from the other end for the remainder of the time and/or may also be sucked alternately from opposite ends.

It is well known that tobacco must be worked through the cigarette making machine with a sufficiently high moisture content to prevent undue breakage of the tobacco in the process of distributing and showering the same to form the cigarette rod.

The moisture content necessary for feeding the tobacco is generally considered too high for the satisfactory packing of the cigarettes into the usual packages, and it is desirable to reduce the moisture content both for the purpose of preventing the cigarettes from going mouldy, and for improving their smoking quality.

According to the present invention, apparatus for conditioning cigarettes (e. g. passing dry and/or warm air therethrough in an axial direction) comprises in combination a movable carrier for cigarettes, and one or more pairs of air ducts having outlet ports wherein the ports of each pair of ducts are arranged to be in axial alignment with and at opposite ends of a cigarette to be received between them on the carrier, and are also movable with the cigarette carrier.

The word "air" used herein and in the appended claims is intended to include any gas used to reduce the moisture content of the tobacco when passed through the latter.

One form of apparatus for conditioning cigarettes according to the present invention, by passing air through them, will now be described with reference to the accompanying drawings, in which:—

Figure 1 is a side elevation of the apparatus.

Figure 2 is a section along the line 2—2 of Figure 1 looking in the direction of the arrows.

Figure 3 is an enlarged sectional view of the peripheries of the cigarette carrying drums.

Figure 4 is an elevation looking along the line 4—4 of Figure 3, looking in the direction of the arrows.

Figures 5 and 6 are details of the hollow shaft partitions.

Like reference numerals refer to like parts throughout the several figures of the drawings.

Referring to Figure 1 of the drawings, cigarettes to be conditioned are brought along a conveyor 10, which may be the delivery band of a cigarette machine. Successive cigarettes fall off the band 15 into grooves or flutes in pairs of discs 11 which rotate in a clockwise direction. The cigarettes are prevented from inadvertently leaving the discs 11 by circumferential shields 12. The two pairs of discs are mounted in the space between three hollow concentric discs or drums 13, 14, 15, see Figure 2. These three hollow drums are mounted on a hollow rotatable shaft 16 to which they are keyed. The shaft is divided longitudinally into three segments by internal partitions 17 which extend from one end of the shaft to the other. The drums 13 and 15 communicate with the segment 18 of the hollow shaft through arcuate slots 19. The middle, drum 14 communicates with the segments 20 and 21 of the hollow shaft. 30 A casing 22 is clamped over one end of the hollow rotating shaft 16 and acts as an intake for air.

Another set of hollow rotating drums 23, 24 and 25 (see Figure 3) keyed to a hollow rotating shaft 160, is provided at the same level as the drums 13, 14 and 15, and the casing 22 forms a duct which communicates with the hollow shafts of both sets of hollow drums. As seen in Figure 1, a second casing 26, similar to the casing 22 is mounted on the other side of the hollow shafts 16 and 160. The hollow drums 13, 14 and 15, and 23, 24 and 25, are provided with air ducts or nozzles 27 and 28, the outlet ports of which are in axial alignment and between which the cigarettes are mounted so that when the cigarettes are in position, a current of air may pass through the tobacco in the cigarette.

The cigarettes are transferred from the pairs of discs 11 to the drums 13 and 14, or 14 and 15 respectively, and are held in position on the drums in grooves or flutes 29 provided on rings 30 clamped concentrically to the discs. The cigarettes fall by gravity at the transfer point where the shield 12 terminates.

In order that the ends of the cigarettes may be

as close as possible to the ports or nozzles 27 and 28, the latter, which are on the lower pressure side, and are of larger area, are movable towards and away from the opposite ducts 27. The ducts 5 or nozzles 28 are spring urged to move inwardly, as seen more clearly in Figure 3, and are controlled by cams 31 for the first set of drums 13, 14 and 15, and by cams 37 for the second set of drums 23, 24 and 25.

10 The cams are so arranged that the nozzles 28 are pressed back until a cigarette is dropped into position in the grooves 29 of the first set of drums from the pairs of discs 11. After this, the nozzles 28 move inwardly and press against the ends of 15 the cigarettes so that the end faces of each cigarette are in axial alignment with and abut against a pair of nozzles 27 and 28. When this occurs, a current of air can be passed through the tobacco in the cigarette from the nozzles 27 and out from 20 the nozzles 28. The hollow shaft 16 for the discs 13, 14 and 15 is closed at one end by a plate 32 which allows the air stream to enter only the segments 20 and 21.

At the other end of the shaft 16, there is provided a sealing plate 33, as seen in Figure 6, which seals up the segments 20 and 21, and allows the air to pass out only through the segment 18. In this way the air is constrained to pass from the casing 22 to the segments 20 and 21, then through 30 the nozzles 27 and the cigarette tube, and out through the nozzles 28 and the segment 18 into the outlet casing 26. In the drums 13, 14 and 15 the outlet ports or nozzles 28 are mounted on the two outer drums 13 and 15, whereas in the 35 second set of drums 23, 24 and 25 the outlet ports or nozzles 28 are mounted on the center disc 24. The reason for this will be given later.

As the cigarettes, therefore, are delivered from the pairs of discs 11, a current of air passes 40 through each individual cigarette and the latter are carried with the hollow drums as they rotate in an anti-clockwise direction.

The drums which are keyed to the shaft 16 are driven through a toothed wheel 180 mounted on 45 the drum 13.

Shields 34 formed concentrically with these hollow drums 13, 14 and 15 are provided to retain cigarettes against outward movement. The cigarettes are brought up to the leading edge 35 of the cams 31, and these cams are arranged in the path of pins 280 rigidly connected to the nozzles 28 so that the latter are pushed away from the opposite nozzles 27 at a time when the cigarettes are to be transferred into slots in pairs of discs 36. These discs 36 are rotated in a clockwise direction, and shields 371 concentric with the discs 36 and commencing at the transfer point act as strippers and cause the cigarettes to be removed from the grooves in the drums 13, 14 and 15 and carried round in the grooves in the discs 36.

The cigarettes are then carried to the periphery of the pairs of hollow drums 23 and 24, and 24 and 25, respectively. The cigarettes, when they 65 are opposite the cams 37 are dropped into the grooves 29 in the pairs of hollow drums 23 and 24, and 24 and 25 respectively, and after this has taken place, the nozzles 28 are released by the cams 37 to allow the nozzles to press against the 70 cigarettes.

The operation is the same as in the case of the drums 13, 14 and 15. In the case of the drums 23, 24 and 25, however, the outlet nozzles 28 are on the middle drum 24.

75 In the second set of drums 23, 24 and 25 the

drums 23 and 25 communicate with the segment 180 of the hollow shaft 16, and the drum 24 communicates with the segments 200 and 210. In this case a plate such as 33 shown in Figure 6 is placed on the intake end of the shaft 160, that is, under the casing 22 while a plate such as 32 is placed on the other end of the shaft.

In this way, as the cigarettes are carried in the first set of drums, the air passes through the cigarettes in one direction, and when they 10 are on the second set of drums the air passes through the cigarettes in the opposite direction. The cigarettes are carried round by the drums 23 and 24 or 24 and 25 as in the case of the drums 13 and 14, and 14 and 15. Circumferential shields 38 prevent the cigarettes from moving outwardly. The cigarettes are picked off the drums 23 and 24 and 24 and 25 respectively by pairs of discs 39 in a similar manner to that in which the cigarettes were removed 20 from the drums 13, 14 and 15 by the discs 36 and cam 31.

The cigarettes may be delivered from the discs 39 on to a conveyor, not shown, in any well known manner.

25 The drums in which the drying takes place are adjustable axially in order to accommodate various lengths of cigarette, and the current of air passing through the cigarettes may be caused by applying super-atmospheric pressure on the 30 side of the casing 22, or sub-atmospheric pressure (e. g. suction) on the side of the casing 26, and the air itself may be heated before it is passed through the cigarettes.

Where it is desired to heat the air it is preferable to provide the heating unit within the drying apparatus and this is most conveniently effected by fitting electric heaters within the drums 13 and 15 as shown at 40 Figure 2, and within the drum 24 as shown at 40 Figure 3. 40 The heaters consist of resistance wire wound on insulating formers and the connection for the current is made by slip rings and brushes (not shown) the rings being mounted on either of the drums or the ring.

It will also be understood that any desired flavouring may be imparted to the draught of air which will readily be absorbed by the tobacco, owing to the well known property of tobacco of quickly absorbing such flavours.

50 The invention is particularly, but not exclusively, applicable in cases where cigarettes are being packed immediately they come from the cigarette making machine where the drying discs above described may readily be located between 55 the points where the cigarettes emerge from the cigarette machine, and the point where they are delivered direct to the packing machine.

What I claim as my invention and desire to 60 secure as Letters Patent is:—

1. Apparatus for conditioning cigarettes, comprising in combination a movable carrier for the cigarettes, a pair of oppositely directed and aligned nozzles for each cigarette, said nozzles being movable with the carrier and relatively 65 movable towards and away from one another, means for controlling the relative movement of the nozzles, and means connected with the inlet of one of the nozzles whereby a fluid may be passed through the cigarette held between the 70 nozzles.

2. Apparatus for conditioning cigarettes, comprising in combination a movable carrier for the cigarettes, at least one pair of oppositely directed and aligned nozzles, said nozzles being 75

movable with the carrier and relatively movable towards and away from one another, means for controlling the relative movement of the nozzles to engage opposite ends of the cigarettes, and means connected with the inlet of one of a pair of nozzles whereby fluid may be passed through a cigarette held between the nozzles.

3. Apparatus for conditioning cigarettes, comprising in combination a movable carrier for the cigarettes, said carrier comprising a pair of rotatable members, spaced apart and having their axes of rotation in alignment, at least one pair of oppositely directed and aligned nozzles, for each cigarette, each nozzle of a pair being mounted on one of the said rotatable members, said nozzles being movable with the carrier and relatively movable towards and away from one another, means for controlling the relative movement of the nozzles, and means connected with the inlet of one of a pair of nozzles whereby fluid may be passed through a cigarette held between the nozzles.

4. Apparatus for conditioning cigarettes, comprising in combination a movable carrier for the cigarettes, said carrier comprising a pair of rotatable members spaced apart and having their axes of rotation in alignment, at least one pair of oppositely directed and aligned nozzles, for each cigarette, each nozzle of a pair being mounted on one of the said rotatable members, said nozzles being movable with the carrier and relatively movable towards and away from one another to engage opposite ends of the cigarettes, and means connected with the inlet of one of a pair of nozzles whereby fluid may be passed through a cigarette held between the nozzles.

5. Apparatus for conditioning cigarettes, comprising in combination a rotatable carrier for the cigarettes, said carrier comprising in combination two axially aligned rotatable hollow drums, at least one pair of oppositely directed and aligned nozzles mounted on said drums, said nozzles being relatively movable towards and away from one another and each nozzle communicating with the interior of the drum on which it is mounted, a hollow shaft for supporting the drums, said hollow shaft being divided into separate compartments, each of which is provided with an aperture which communicates with the interior of one drum only of a pair of drums, means for controlling the relative movement of the nozzles, and means connected with said hollow shaft whereby a fluid may be passed through a cigarette held between a pair of nozzles.

6. Apparatus for conditioning cigarettes, comprising in combination a rotatable carrier for the cigarettes, said carrier comprising in combination two axially aligned rotatable hollow drums, at least one pair of oppositely directed and aligned nozzles mounted on said drums, said nozzles being relatively movable towards and away

from one another and each nozzle communicating with the interior of the drum on which it is mounted, a hollow shaft for supporting the drums, said hollow shaft being divided into separate compartments, each of which is provided with an aperture which communicates with the interior of one drum only of a pair of drums to engage opposite ends of the cigarettes, means for controlling the relative movement of the nozzles, and means connected with said hollow shaft whereby a fluid may be passed through a cigarette held between a pair of nozzles.

7. Apparatus for conditioning cigarettes, comprising in combination a movable carrier for the cigarettes, a pair of oppositely directed and aligned nozzles for each cigarette, said nozzles being movable with the carrier and relatively movable towards and away from one another to engage opposite ends of the cigarettes, means for controlling the relative movement of the nozzles whereby the cigarettes may be engaged and released at the proper time, and means connected with one of said nozzles whereby a fluid may be passed through a cigarette held between the nozzles.

8. Apparatus for conditioning cigarettes, comprising in combination a movable carrier for the cigarettes, a pair of oppositely directed and aligned nozzles for each cigarette, said nozzles being movable with the carrier and relatively movable towards and away from one another, means for controlling the relative movement of the nozzles, means for delivering one cigarette at a time between each pair of nozzles, said means comprising in combination at least one rotatable member having peripheral pockets for the cigarettes, means for feeding the cigarettes one at a time into the pockets with their axes parallel to the axis of rotation of said rotatable member, and means connected with one of said nozzles whereby a fluid may be passed through a cigarette held between the nozzles.

9. Apparatus for conditioning cigarettes, comprising in combination a movable carrier for the cigarettes, at least one pair of oppositely directed and aligned nozzles, said nozzles being movable with the carrier and relatively movable towards and away from one another, means for controlling the relative movement of the nozzles to engage opposite ends of the cigarettes, means for delivering one cigarette at a time between each pair of nozzles, said means comprising in combination at least one rotatable member having peripheral pockets for the cigarettes, means for feeding the cigarettes one at a time into the pockets with their axes parallel to the axes of rotation of said rotatable member, and means connected with one of a pair of nozzles whereby a fluid may be passed through a cigarette held between the nozzles.

WALTER EVERETT MOLINS.
